US0D1064739S

(12) **United States Design Patent** (10) **Patent No.:** **US D1,064,739 S**
(45) **Date of Patent:** **** Mar. 4, 2025**

(54) **BEVERAGE CONTAINER**

(71) Applicant: **Pacific Market International, LLC**,
Seattle, WA (US)
(72) Inventors: **Andrew C. F. Wahl**, Seattle, WA (US);
Matthew Kenneth Dolph, Seattle, WA (US)
(73) Assignee: **Pacific Market International, LLC**,
Seattle, WA (US)

(**) Term: **15 Years**

(21) Appl. No.: **29/806,429**

(22) Filed: **Sep. 2, 2021**

(51) LOC (15) Cl. **07-01**

(52) U.S. Cl.

USPC **D7/510; D7/509**

(57) **CLAIM**

The ornamental design for a beverage container as shown and described.

DESCRIPTION

FIG. 1 is a top perspective view of a beverage container showing our new design.

FIG. 2 is a bottom perspective view thereof.

FIG. 3 is a left side elevational view thereof.

FIG. 4 is a rear elevational view thereof.

FIG. 5 is a right side elevational view thereof.

FIG. 6 is a front elevational view thereof.

FIG. 7 is a top plan view thereof.

FIG. 8 is a bottom plan view thereof.

FIG. 9 is a top perspective view of a second embodiment thereof.

FIG. 10 is a bottom perspective view thereof.

FIG. 11 is a left side elevational view thereof.

FIG. 12 is a rear elevational view thereof.

FIG. 13 is a right side elevational view thereof.

FIG. 14 is a front elevational view thereof.

FIG. 15 is a top plan view thereof; and,

FIG. 16 is a bottom plan view thereof.

The broken lines depict portions of the beverage container that form no part of the claimed design.
